United States Patent

Des. 234,773
Patented Apr. 8, 1975

234,773

ELECTRONIC CALCULATOR

Lewis H. Herr, Lansdale, and John S. Kovacs, East Norriton, Pa., assignors to Sperry Rand Corporation, New York, N.Y.

Filed Sept. 26, 1973, Ser. No. 401,041

Term of patent 14 years

Int. Cl. D18—01

U.S. Cl. D26—5 C

FIG. 1

FIG. 2

FIG. 3

FIG. 4

FIG. 5

FIG. 6

FIG. 1 is a top view of an electronic calculator showing our new design;

FIG. 2 is a left side elevational view;

FIG. 3 is a front elevational view;

FIG. 4 is a bottom view;

FIG. 5 is a right side elevational view;

FIG. 6 is a rear elevational view.

The numbers shown in FIG. 1 are shown in broken lines for illustrative purposes only.

What we claim is:

The ornamental design for an electronic calculator, substantially as shown and described.
